Patented Sept. 21, 1971

222,006

END CLOSURE FOR A NEWSPAPER DELIVERY TUBE

Paul H. Pennell, North Jackson, Ohio, assignor to
Elastomeric Products Inc., North Jackson, Ohio

Filed May 6, 1970, Ser. No. 22,830

Term of patent 14 years

Int. Cl. D31

U.S. Cl. D74—9

FIG. 1 is a perspective view of an end closure for a newspaper delivery tube showing the front, top and one side thereof.

FIG. 2 is a perspective view thereof showing the back, top and the other side.

FIG. 3 is a side elevation thereof; and

FIG. 4 is a cross sectional view thereof of line 4—4 of FIG. 3.

I claim:

The ornamental design for an end closure for a newspaper delivery tube, as shown.
